T. GLASSEY

VISE

Filed Sept. 20, 1926

FIG. 1.

FIG. 2.

FIG. 3.

FIG. 4.

FIG. 5.

Inventor
Thomas Glassey.
By Clarence A. O'Brien.
Attorney

UNITED STATES PATENT OFFICE.

THOMAS GLASSEY, OF RED BANK, NEW JERSEY.

VISE.

Application filed September 20, 1926. Serial No. 136,558.

The present invention relates to improvements in vises, and has for its principal object to provide a simple and efficient means for adjusting the movable jaw with respect to the coacting stationary jaw whereby the parts will be secured in their properly adjusted positions against accidental movement, thus assuring the efficiency of the use of the device.

10 A further object is to provide a vise which obviates the use of the usual screw threaded shaft carrying the movable jaw in order to adjust the same with respect to the stationary jaw, thus saving considerable time and 15 labor in the adjustment of the vise.

A further object is to provide a vise of the above mentioned character which is simple in construction, inexpensive, strong, and durable and further well adapted to the 20 purpose for which it is designed.

Other objects and advantages of the invention will become apparent during the course of the following description taken in connection with the accompanying drawing.

25 In the accompanying drawing forming a part of this application and in which like numerals designate like parts throughout the several views:

Figure 1 is a longitudinal sectional view 30 through the vise embodying my invention.

Figure 2 is a top plan view thereof, the cover or top of the casing being removed.

Figure 3 is a sectional view taken approximately on line 3—3 of Figure 1.

35 Figure 4 is a bottom plan view of the removable cover or top, and

Figure 5 is a fragmentary detail showing the locking pawl in its dropped position of the shaft.

40 In the drawing wherein for the purpose of illustration is shown the preferred embodiment of my invention, the numeral 1 designates generally a substantially rectangular shaped casing, which includes 45 the sides 2 and the forward and rear ends 3 and 4 respectively. Formed on the upper portion of the forward end 3 and extending above the top of the casing is the stationary jaw 5.

50 A cover or top plate 6 is adapted to be secured on the upper edges of the side 2 of the casing 1, suitable openings 7 being formed in the cover or top plate 6 adjacent the longitudinal side edges thereof for co-operation with similar openings 8 formed

in the upper edge of the side members 2 for receiving suitable fastening means. The forward end of the cover is cut out as indicated at 9 to accommodate the portion of the stationary jaw which extends above the top of the casing. A series of transversely extending ratchet teeth 10 formed on the bottom of the cover or top plate 6 in the central portion thereof and the purpose of these ratchet teeth will hereinafter be more fully 65 described.

Suitable guides 11 are formed on the inner faces of the sides to the casing 1 adjacent the upper edges thereof said guide members extending longitudinally of the 70 casing. Additional longitudinally extending guides 12 are formed on the inner opposed faces of the sides 2, adjacent the bottom edges thereof, and as is more clearly illustrated in Figure 3, the lower guides extend inwardly further than the upper 75 guides.

Adapted for slidable movement within the casing 1 is a substantially rectangular shaped block 13, the bottom of said block 80 is slidable along the upper faces of the lower guides 12, and is of such width as to be disposed between the guides 11. A rib 14 is formed on the bottom of the block 13, and is adapted to extend downwardly between 85 the lower guides 12, as is more clearly illustrated in Figure 3. In this manner, the block 13 will be adapted to slide longitudinally within the casing and freely between the guide members provided therefor.

Extending through the forward end 3 of the casing, and having its inner end extending through the passage 13' formed in the upper portion of the slidable block 13, is the rotatable shaft 15. The inner end portion of the passage 13' is threaded for co-operation with threaded portion 15' of the shaft 15, in securing fine or close adjustment of the jaws. The outer end of the rotatable shaft 15 extends through the relatively thick plate member 17 on the upper portion of which is formed the jaw 18 which jaw is movable with respect to the stationary jaw 5 and is further adapted for co-operation therewith. A handle 19 is secured on the outer end of the shaft and this handle engages the outer face of the plate 17, a cotter pin 20 extending through the shaft adjacent the inner face of the plate 17 so that the movable jaw will be carried 105 110

by the shaft and will slide simultaneously therewith, as will be hereinafter more clearly described.

In order that the plate-like member 17 and the jaw 18 carried thereby may be maintained in proper parallel spaced relation with respect to the forward end 3, and the stationary jaw 5 formed thereon, there is provided a pair of guide rods 21, the outer ends thereof extending into the bottom portion of the member 17. These rods extend through the lower portions of the forward ends 3 of the casing 1 and are slideable in suitable longitudinally extending openings provided therefor in the lower guides 12 which are formed on the inner faces of the respective sides of the casing in the manner as clearly illustrated in Figures 1 and 3.

A substantially rectangular shaped recess 22 is formed in the top of the block 13, and this recess communicates with the horizontally disposed opening formed in the block for receiving the shaft 15. Adapted for vertical slideable movement in the recess 22 is the pawl 23, the same being provided with the teeth 24 in the upper face thereof for cooperation with the ratchet teeth 10 formed on the bottom of the cover or top plate 6. A notch 25 is formed in the bottom of the pawl 23, and the purpose thereof will be presently apparent.

The portion of the rotatable shaft 15 which is disposed below the recess 22 is cut away as illustrated at 26 and 27 respectively, whereby a projection 28 is formed in the cavity provided in the shaft 15, and this projection 28 is adapted for cooperation with the notch 25 formed in the bottom of the vertically slideable pawl 23, in the manner as clearly shown in Figure 5.

The inner opposed faces of the coacting jaws are provided with the coacting curved serrated portions 29, and are arranged vertically in order that the pipe or other cylindrical object may be clamped in the vise in a vertical position. The jaws are further provided with the coacting curved serrated portions 30 to accommodate a horizontally disposed pipe in the vise.

In operation, the vise is opened by rotating the shaft 15 in one direction through the medium of the handle 19 so that the projection 28 is moved into alinement with the recess or notch 25 formed in the bottom of the pawl 23 and to further bring the cut out portions 26 and 27 of the shaft 15 into registry with the recess 22 so that the pawl 23 will by gravity move downwardly in the recess 22 and enter the cut out portions 26 and 27 and the projection 28 will then be disposed within the notch 25 as is shown more clearly in Figure 5. The lug 16 carried by the inner end of the shaft 15 will engage with the stop 16' arranged on the inner end of the block in limiting the slid-

ing movement of the shaft so that the cut out portion or notch 25 will register with the projection 28. The handle 19 is pulled outwardly, causing the block 13 and the plate-like member 17 which carries the jaw 18 to slide forwardly simultaneously.

After the jaws have been opened to the proper distance to facilitate the insertion of the member which is to be clamped between the jaws, the shaft 15 is rotated in the reverse direction whereupon the projection 28 is moved out of engagement with the notch 25, and the cut out portions 26 and 27 are also moved out of alinement with respect to the recess 22 so that the pawl 23 will be raised or moved upwardly in the recess 22 to cause the teeth 24 to be brought into locked engagement with the adjacent ratchet teeth 10. When the parts are thus arranged as shown in Figure 1, the jaws 5 and 18 will securely hold the member placed between the jaws and there will be no possibility of the movable jaw 18 being accidentally loosened.

The provision of a vise of the above mentioned character will obviate the necessity of having to provide the usual screw threaded shaft which carried the movable jaw and thereby will save considerable time and labor in adjusting the jaws with respect to each other. Furthermore, a device of the above mentioned character will securely hold a pipe or other object in a tightly clamped position in the vise in order that the proper work may be performed on such object.

This vise may be readily and easily adjusted, and will furthermore be strong and durable.

While I have shown the preferred embodiment of my invention it is to be understood that minor changes in the size, shape, and arrangement of parts may be resorted to without departing from the spirit or scope of the invention.

Having thus described the invention, what I claim as new and desire to secure by Letters Patent is:—

1. A vise comprising a casing open at its top, a cover therefor, a stationary jaw at the forward end of the casing, a coacting movable jaw, a block slidably arranged within the casting, a rotatable shaft extending through the forward end of the casing, the inner end of the shaft extending through the block, means for securing the block against sliding movement on the shaft, the outer end of the shaft extending through the movable jaw, means for preventing the sliding movement of the last mentioned jaw on the shaft, a handle secured on the outer end of the shaft for actuating the same, ratchet teeth arranged on the bottom of the cover, a pawl carried by the block and co-operating with the ratchet teeth for securing the movable jaw in its adjusted position with respect to the stationary jaw, and co-

operating means associated with the shaft and the pawl for disengaging the pawl from the ratchet teeth to permit the sliding movement of the shaft and the block, and movable jaw carried thereby.

2. A vise comprising a casing open at its top, a cover therefor, a stationary jaw at the forward end of the casing, a coacting movable jaw, a block slidably arranged within the casing, a rotatable shaft extending through the forward end of the casing, the inner end of the shaft extending through the block, means for securing the block against sliding movement on the shaft, the outer end of the shaft extending through the movable jaw, means for preventing the sliding movement of the last mentioned jaw on the shaft, a handle secured on the outer end of the shaft for actuating the same, ratchet teeth arranged on the bottom of the cover, a pawl carried by the block and cooperating with the ratchet teeth for securing the movable jaw in its adjusted position with respect to the stationary jaw, cooperating means associated with the shaft and the pawl for disengaging the pawl from the ratchet teeth to permit the sliding movement of the shaft and the block, and movable jaw carried thereby, and guide means for said block.
3. A vise comprising a casing open at its top, a cover therefor, a stationary jaw at the forward end of the casing, a coacting movable jaw, a block slidably arranged within the casing, a rotatable shaft extending through the forward end of the casing, the inner end of the shaft extending through the block, means for securing the block against sliding movement on the shaft, the outer end of the shaft extending through the movable jaw, means for preventing the sliding movement of the last mentioned jaw on the shaft, a handle secured on the outer end of the shaft for actuating the same, ratchet teeth arranged on the bottom of the cover, a pawl carried by the block and cooperating with the ratchet teeth for securing the movable jaw in its adjusted position with respect to the stationary jaw, cooperating means associated with the shaft and the pawl for disengaging the pawl from the ratchet teeth to permit the sliding movement of the shaft and the block, and movable jaw carried thereby, guide means for said block, and additional guide means for the movable jaw.

4. A vise comprising a casing open at its top, a cover therefor, a stationary jaw at the forward end of the casing and extending above the top thereof, ratchet teeth arranged on the bottom of the cover, a block slidably arranged within the casing, a shaft extending through the forward end of the casing, the inner end of said shaft extending through the upper portion of the block, means for

preventing the sliding movement of the block on said shaft, whereby the shaft and the block are adapted for simultaneous sliding movement, a jaw member secured on the outer end of the shaft and adapted to coact with the stationary jaw, a handle on the outer end of the shaft for actuating the same, said block being provided with the recess in the top thereof which communicates with the opening through which the inner end of the shaft extends, a pawl arranged within said recess, teeth formed on the upper face of the pawl adapted for cooperation with the ratchet teeth on the under side of the cover whereby the block and the shaft are locked against sliding movement to hold the jaw in proper adjusted position, the portion of the shaft disposed below the recess formed in the block being cut out to receive the lower portion of the pawl when the shaft is turned in one direction whereby the pawl is moved to an inoperative position to facilitate the sliding movement of the block and the shaft.

5. A vise comprising a casing open at its top, a cover therefor, a stationary jaw at the forward end of the casing and extending above the top thereof, ratchet teeth arranged on the bottom of the cover, a block slidably arranged within the casing, a shaft extending through the forward end of the casing, the inner end of said shaft extending through the upper portion of the block, means for preventing the sliding movement of the block on said shaft, whereby the shaft and the block are adapted for simultaneous sliding movement, a jaw member secured on the outer end of the shaft and adapted to coact with the stationary jaw, a handle on the outer end of the shaft for actuating the same, said block being provided with a recess in the top thereof which communicates with the opening through which the inner end of the shaft extends, a pawl arranged within said recess, teeth formed on the upper face of the pawl adapted for cooperation with the ratchet teeth on the under side of the cover whereby the block and the shaft are locked against sliding movement to hold the jaw in proper adjusted position, the portion of the shaft disposed below the recess formed in the block being cut out to receive the lower portion of the pawl when the shaft is turned in one direction whereby the pawl is moved to an inoperative position to facilitate the sliding movement of the block and the shaft, the bottom of the pawl being provided with a notch, and a projection extending upwardly of the bottom of the cavity and adapted to enter the notch when the pawl is in its lowermost position.

In testimony whereof I affix my signature.

THOMAS GLASSEY.
